UNITED STATES PATENT OFFICE.

THOMAS J. STURTEVANT, OF WELLESLEY, MASSACHUSETTS, ASSIGNOR, BY MESNE ASSIGNMENTS, TO STURTEVANT MILL COMPANY, OF BOSTON, MASSACHUSETTS, A CORPORATION OF MASSACHUSETTS.

CRUSHING-MILL.

1,360,466.

Specification of Letters Patent. Patented Nov. 30, 1920.

Application filed June 15, 1917. Serial No. 174,875.

To all whom it may concern:

Be it known that I, THOMAS J. STURTEVANT, a citizen of the United States, residing at Wellesley, county of Norfolk, and State 5 of Massachusetts, have invented an Improvement in Crushing-Mills, of which the following description, in connection with the accompanying drawings, is a specification, like characters on the drawings representing, like characters on the drawings repre-

10 senting like parts.

The invention hereinafter described relates to crushing mills for reducing materials, of the general class shown in Letters Patent of the United States, No. 995,580, dated June 20, 1911; No. 1,000,457, dated 15 August 15, 1911; and No. 1,105,713, dated August 4, 1914.

A mill of this class comprises a plurality of crusher rolls on carriers having arms 20 projecting radially inward to engage a central floating washer having a pivotal bearing on an adjustable pin carried by a spider, the arms of which are drawn inward toward the ring by helical springs.

25 The rolls, carriers, washer, spider and springs are all mounted on and supported by a head or door which is hinged to the casing containing the ring and rolls.

These mills experience very heavy duty 30 and sometimes operate under a pressure of several tons. Consequently, the parts must be of massive, expensive construction.

One of the objects of the present invention is to reduce the number of parts and 35 the mass carried by the door, and provide a mill which is simpler, lighter and cheaper to manufacture than the mills shown in said patents.

When upper and lower crusher rolls are 40 used, gravity tends to pull the upper roll away from the inner surface of the ring, while it tends to pull the lower roll toward the ring. Heretofore, supplemental springs, such, for example, as shown in the aforesaid 45 Letters Patent, No. 1,105,713, have been provided for the rolls to counteract the effect of gravity thereon.

Another object of the present invention is to provide means for independently varying 50 the tension of the springs acting on the rolls, so that the pressure may be distributed to the rolls as desired, and the springs for the rolls may be adjusted to compensate for the effect of gravity thereon, and thereby

eliminate the necessity for the supplemental 55 springs referred to.

Another object of the invention is to provide means for pressing the rolls toward the ring, which will permit the door to be opened easily and readily for the inspection 60 of the parts in the casing and the parts carried by the door.

Still another object of the invention is to provide simple and effective means for adjusting the rolls toward or from the inner 65 face of the ring to take up wear on the parts and vary the distance of the rolls from the ring as desired.

With the aforesaid and other objects in view, the character of the invention will be 70 best understood by reference to the following description of embodiments thereof shown in the accompanying drawings, wherein:

Figure 1 is a side elevation of a crushing 75 mill shown herein as embodying the invention;

Fig. 2 is a vertical section through the mill shown in Fig. 1;

Fig. 3 is a side elevation of the mill; 80

Fig. 4 is a vertical section taken on line 4—4 of Fig. 2;

Fig. 5 is a vertical section of a modified form of the invention; and

Fig. 6 is a side elevation of the mechanism shown in Fig. 5. 85

Referring to the drawings, the crushing mill shown therein as embodying the invention comprises a base 1 (Figs. 1 and 2) supporting a casing 3 containing an anvil ring 90 5 having a concave inner crushing face 7. This ring is mounted on a spider 9 having a hub 11 fast on a shaft 13 journaled in bearings 15 mounted on the base referred to. The shaft has a pulley 17 fast 95 thereon which may be driven by a belt (not shown) from a suitable source of power.

One or more crusher rolls may be mounted within and coöperate with the anvil ring to crush material fed therebetween. In the 100 present instance of the invention, three rolls 19 (Figs. 2 and 4) are shown having convex faces curved to conform to the concave face of the ring. These rolls are journaled on carriers, in the present instance of the invention, in the form of shafts 21 projecting laterally outward from the casing and mounted in boss bearings 23 integral with yokes 25

(Fig. 3) having ends journaled in bearings 27 mounted on the outer face of a head or door 29 movable to open and closed positions. To permit this movement of the door, 5 it may have hinged arms 31 projecting therefrom above and resting on arms 33 integral with the casing. A hinge pin 35 projects through registering holes in said arms. The door may be secured in closed position by 10 screws 37 projecting loosely through ears on said door and threaded into similar ears on said casing. One of these screws 37^a may be longer than the others and project through elongated slots in its ears and be threaded to 15 a nut 37^b set in a recess in the ear on the casing to facilitate closing of the door, as more fully hereinafter described. To facilitate opening of the door, a screw 39 may be provided threaded in an extension 41 of the 20 ear for the screw 37^a and adapted to bear and react against an abutment on the casing.

The roll carriers pivotally mounted on the door as described will permit the rolls to move toward and from the inner face of the 25 ring. Next will be described the means for pressing the rolls toward the ring. To accomplish this, each carrier may have an arm 43 (Figs. 1, 2 and 3) projecting radially outward beyond the casing and having its free 30 end engaging the outer end of a pin 45, the inner end of which is rounded and seated in the socket of a plunger 47 in a cylinder 49 mounted on the outer face of the casing. This plunger is pressed toward the right of 35 Fig. 2 by a helical spring 51 mounted in said socket. The tension of said spring may be varied by a screw 53 threaded in an end of said cylinder and engaging a disk 55 bearing against the spring. The movement of the 40 spring toward the carrier may be limited by a head 57 detachably secured to said cylinder, and having a neck 59 projecting therefrom to contribute to the support of the pin, as more fully hereinafter described.

45 By the construction described, the helical springs will operate through the pins 45 and carrier arms 43 to rock the carriers and press the crusher rolls outward toward the inner face of the ring. The springs may be so adjusted that when the material to be crushed is fed between the ring and rolls, the latter will be moved inward away from the ring and rock their carriers against their springs and compress the latter with the tension required for producing efficient crushing 50 pressure.

As stated, gravity tends to pull the upper roll away from the inner face of the ring, and tends to pull the lower rolls toward said 60 face. The screw and disk for the spring of the upper roll may be adjusted to apply a tension to said spring which is greater than the tension applied to the springs for the lower rolls, and thus counteract the effect of 65 gravity on the rolls.

From time to time it may be desirable to vary the distances of the rolls from the inner face of the ring to compensate for wear on the rolls and ring and to adapt the mill to varying conditions. To accomplish this, 70 the carrier shafts 21 may have portions 58 (Fig. 2) with axes eccentric to portions 59 mounted in bearings 23. Rotative adjustment of said shaft will cause the eccentric portions to present their rolls nearer to or 75 farther from the ring as required. To secure the shafts in their different positions of rotative adjustment, each bearing may be provided with a key 61 (Figs. 2 and 3) adapted to enter any of the key slots 63 distributed at intervals circumferentially of the 80 shaft. The key may be held to prevent its sliding axially of the shaft by a set screw 65.

The carriers project through elongated openings 67 (Fig. 2) in the head to allow the 85 rocking of the carriers. To prevent escape of dust from the casing through said openings, they may be covered by guard plates 69 movable with the carriers.

The material to be crushed may be fed 90 into the mill through the usual hopper 71 (Fig. 1) and a spout 73, the latter being mounted on the door and directing the material to the inner surface of the ring.

When it is desired to inspect or repair the 95 parts within the casing and the parts carried by the door, the latter is swung on its hinges to its open position. To accomplish this, the screws 37 are released and then the opening screw 39 is adjusted to force the 100 door ajar. Then the door may be swung to its open position, and in the course of this movement the carrier arms 43 will move automatically away from the spring-pressed pins 45. After the rolls have moved away 105 from the ring, they may drop downward until their carriers are limited by the lower ends of the elongated slots in the door.

When it is desired to close the door, it 110 may be swung on its hinges back toward the casing, and in the course of this movement the carrier arms will automatically come into engagement with the pins 45, thereby 115 rocking the rolls outward toward the die to their operative position. The screw 37^a referred to is of sufficient length to catch into threaded engagement with the nut 37^b before the rolls are moved outwardly as described. This screw may be tightened and will afford sufficient mechanical advantage 120 to complete the closing movement of the door, and thereby rock the roll carriers away from the ends of the slots in the door supporting them while the door is open.

In the modification shown in Figs. 5 and 125 6, a somewhat different mechanism is provided for pressing the crusher rolls outward toward the die. Each carrier is pivotally connected to a yoke 75 having an adjusting screw 77 bearing on the outer free 130

end of an arm 79 pivoted on a bracket 81 on a plate 82 mounted on the casing. The arm is urged outwardly by a helical spring 83 confined between a socket 85 on the arm and 5 the outer face of said plate. To limit outward movement of said arm, a bolt 87 may be provided having a head seated in a recess beneath a boss 89 on said plate, said bolt projecting upward through said spring and 10 arm and having an adjusting nut above said arm.

By the construction just described, the springs will rock the arms outwardly and the latter in turn will act on the yokes to 15 draw the carriers and the rolls outwardly.

When it is desired to open the door, the screws 77 may be released sufficiently to permit the yokes to be rocked outwardly away from the arms 79. Then the door may be 20 swung on its hinges to its open position as described. The door may be closed as before, and then the yokes are swung inward to the free ends of the arms, and the screws 77 are tightened sufficiently to return to 25 their original positions of adjustment. The adjusting screws 77 and 87 may be set in different positions to vary the effective tension of the springs on the rolls as desired.

It will be observed that by the constructions described the door is relieved from the burden of supporting the springs, the heavy spider and the washer which are mounted on the door in the mills shown in the aforesaid 30 patents. Also, this permits the carriers and the door to be of lighter simpler construction. In fact, the entire organization may 35 be of a lighter, simpler construction, the parts of which are cheaper to manufacture and easier to assemble and operate.

40 It will be understood that the invention is not limited to the specific embodiments shown, but that various deviations may be made therefrom without departing from the spirit and scope of the appended claims.

45 Claims.

1. In a crushing mill, the combination of a casing, a head thereon movable to open and closed positions, hinge means connecting said head with said casing, an anvil ring mounted in said casing, a plurality of crusher rolls opposed to the inner face of 50 said ring, carriers for said rolls pivotally mounted on and supported by said head to swing with the latter as it moves to open and closed positions, and spring-pressed members mounted on said casing, acting on said carriers to press said rolls toward said ring, said spring-pressed members and carriers having provision for automatically 55 separating on movement of said head to open position, and for automatically operatively engaging on movement of said head to closed position.

2. In a crushing mill, the combination of

a casing, a head thereon movable to open 65 and closed positions, hinge means connecting said head with said casing, an anvil ring mounted in said casing, a plurality of crusher rolls opposed to the inner face of said ring, carriers for said rolls pivotally 70 mounted on and supported by said head to swing with the latter as it moves to open and closed positions, and spring-pressed members mounted on said casing, acting on said carriers to press said rolls toward said ring, 75 said carriers being movable to engage and automatically tension said spring-pressed members on closing movement of said door.

3. In a crushing mill, the combination of a casing, a head thereon movable to open 80 and closed positions, hinge means connecting said head with said casing, an anvil ring mounted in said casing, a plurality of crusher rolls opposed to the inner face of said ring, carriers for said rolls pivotally 85 mounted on said head and having outwardly projecting arms, members mounted on said casing adjacent said arms, and springs for pressing said members toward said arms to move the rolls toward said ring, said arms 90 being movable on opening movement of said head to reduce tension on said springs and then separate from said members.

4. In a crushing mill, the combination of a casing having a door hinged thereto 95 adapted to swing to open and closed positions, an anvil ring mounted in said casing, a carrier pivotally mounted on said door having a shaft projecting into said casing, and an arm projecting outwardly externally 100 of said casing, a roll on said shaft for co-operation with said ring to reduce materials fed between them, a member mounted on said casing adjacent said arm, and spring means for pressing said member into engagement with said arm to move said roll toward said ring, said arm being automatically 105 movable into and out of engagement with said member incidentally to closing and opening movements of said door. 110

5. In a crushing mill, the combination of a casing, a cylinder mounted thereon, a pin projecting outwardly from one end of said cylinder, a coil spring mounted in said cylinder for pressing said pin outwardly 115 through said end, a door hinged to said casing, an anvil ring mounted in said casing, a carrier pivotally mounted on said door and movable therewith, and a roll on said carrier co-operating with said ring to reduce 120 materials fed between them, said carrier being automatically movable into and out of operative engagement with said pin on closing and opening movements of said door.

In testimony whereof, I have signed my 125 name to this specification.

THOMAS J. STURTEVANT.
